DESIGN FOR A COMBINED SWING SPOUT AND VALVE HOOD

Jacques Stanitz, Warren, Ohio, assignor to Mulling Manufacturing Corporation, Salem, Ohio, a corporation of New York

Application December 28, 1944, Serial No. 117,115

Term of patent 7 years

(Cl. D91—1)

To all whom it may concern:

Be it known that I, Jacques Stanitz, a citizen of the United States, residing at Warren, in the county of Trumbull and State of Ohio, have invented a new, original, and ornamental Design for a Combined Swing Spout and Valve Hood, of which the following is a specification, reference being had to the accompanying drawing, forming part thereof.

Figure 1 is a perspective view of a combined swing spout and valve hood showing my new design; and Fig. 2 is a side view thereof.

I claim:

The ornamental design for a combined swing spout and valve hood, substantially as shown.

JACQUES STANITZ.
